UNITED STATES PATENT OFFICE

OSCAR B. ANDERSON, OF ROSELLE, NEW JERSEY, ASSIGNOR TO EAGLE PENCIL COMPANY, OF NEW YORK, N. Y., A CORPORATION OF DELAWARE

DESIGN FOR A PENCIL

Application filed February 27, 1933. Serial No. 47,337. Term of patent 14 years.

To all whom it may concern:

Be it known that I, OSCAR B. ANDERSON, a citizen of the United States of America, residing at No. 258 5th Avenue West, Roselle, New Jersey, have invented a new, original, and ornamental Design for a Pencil, of which the following is a specification, reference being had to the accompanying drawing, forming part thereof, in which

Figs. 1-4 are side views of the pencil, each successive figure showing the pencil turned at an angle of approximately ninety degrees from the next preceding figure.

I claim:

The ornamental design for a pencil, as shown.

OSCAR B. ANDERSON.
